(57) **CLAIM**

The ornamental design for an expansive screen for immersive viewing experience, as shown and described.

DESCRIPTION

FIG. 1 is a rear perspective view of the expansive screen for immersive viewing experience showing the design in a partial cutaway environmental view of a portable inflatable theatre; FIG. 2 is a front perspective view thereof; FIG. 3 is a side view thereof; FIG. 4 is a top view thereof; FIG. 5 is an opposing side view of the side shown in FIG. 3; FIG. 6 is a rear view thereof; FIG. 7 is a front view thereof; FIG. 8 is a side section environmental view thereof illustrating the expansive screen for immersive viewing experience in a portable inflatable theatre; FIG. 9 is a rear perspective view of another embodiment of the expansive screen for immersive viewing experience showing the design in a partial cutaway environmental view of a portable inflatable theatre; FIG. 10 is a front perspective view thereof; FIG. 11 is a side view thereof; FIG. 12 is a top view thereof; FIG. 13 is an opposing side view of the side shown in FIG. 11; FIG. 14 is a rear view thereof; FIG. 15 is a front view thereof; and, FIG. 16 is a side section environmental view thereof illustrating the expansive screen for immersive viewing experience in a portable inflatable theatre. The bottom views are disclaimed in the embodiments shown. The broken lines shown herein are for illustrative purposes only and form no part of the claimed design.
